UNITED STATES PATENT OFFICE.

ALFRED COPONY, OF CHICAGO, ILLINOIS, ASSIGNOR TO WILLIAM H. MINER, OF CHICAGO, ILLINOIS.

COMBINED CAST-STEEL AND WROUGHT-IRON YOKE.

1,131,041.

Specification of Letters Patent.

Patented Mar. 9, 1915.

Application filed March 23, 1914. Serial No. 826,807.

To all whom it may concern:

Be it known, that I, ALFRED COPONY, a subject of the Emperor of Austria-Hungary, residing in Chicago, in the county of Cook 5 and State of Illinois, have invented a new and useful Improvement in Combined Cast-Steel and Wrought-Iron Yokes, of which the following is a specification.

This invention relates to improvements in 10 combined cast steel and wrought iron yokes.

An object of the invention is to provide a yoke suitable for use in railway draft riggings which is composed partly of steel castings and partly of wrought iron, the parts 15 being so arranged that the yoke embodies all the advantages of the two different kinds of metal of which it is made.

Another object of the invention is to provide a combined cast steel and wrought iron yoke which may be used in a horizontal position and attached to the coupler by means 20 of a connecting key...

The invention furthermore consists in the improvements in the parts and devices and 25 in the novel combinations of the parts and devices herein shown, described or claimed.

In the drawing forming a part of this specification, Figure 1 is a side elevation of 30 one form of yoke embodying my improvements. Fig. 2 is a top plan view of the structure shown in Fig. 1. Figs. 3 and 4 are vertical, sectional views taken on the lines 3-3 and 4-4, respectively of Fig. 2. 35 Fig. 5 is a rear end elevation of the yoke. Fig. 6 is a side elevation of another form of yoke embodying my improvements. Fig. 7 is a top plan view of the structure shown in Fig. 6. Fig. 8 is a vertical, sectional view 40 taken on the line 8-8 of Fig. 7 and Fig. 9 is a rear end elevation of the yoke shown in Figs. 6 and 7.

Referring now more particularly to the 45 form of yoke shown in Figs. 1 to 5 inclusive, 10, 10 denote two pieces of wrought iron, each of which forms a side arm of the yoke and a part of the rear portion thereof. Each strap of wrought iron has two horizontally 50 extending portions 11 and a curved, bent end 12 which encircles an elongated boss 13 on the outer side of the steel casting 14, the castings 14 being each provided with a longitudinally extending slot 15 adapted to receive a coupler connecting key therethrough. Each casting 14, on its inner face,

is beveled as shown at 16, 16 to provide for freedom of movement between the yoke and coupler. The rear ends of the wrought iron straps 10 abut each other in the central line of the yoke, as indicated at 17 and the two 60 pieces of wrought iron are firmly and rigidly connected to each other by means of a wrought iron clip 18 having tongues 19 bent therearound and brought together on the rear side of the yoke, as indicated at 20. 65 The clip 18, as clearly shown in the drawing, also forms a filler at the rear end of the yoke against which the rear follower of the draft rigging may abut and be moved thereby. 70

In the structure shown more particularly in Figs. 6 to 9 inclusive, two straps of wrought iron 110, 110, are used, each of which, at its forward end, is bent around and encircles an elongated boss 113 on a 75 steel casting 114, each of the castings 114 being provided with elongated slots 115 adapted to receive therethrough, a coupler connecting key. Each of the castings 114 is furthermore provided on its inner side 80 with beveled faces 116, 116. The rear ends of the wrought iron straps are brought together as indicated at 117 and the same are secured together by means of a filler plate 118 secured thereto by rivets 121. In the 85 structure shown in Figs. 6 to 9, it will be noted that the width of the yoke throughout the lengths of both arms and rear portion is the same, thus differing somewhat from the yoke shown in Figs. 1 to 5 inclusive 90 where the curved end portions of the wrought iron straps are offset where the same encircle the bosses of the steel castings. To maintain the vertical width of the arms of the yoke constant throughout its length, 95 portions of the metal thereof are upset, as indicated at 122 where the straps encircle the bosses of the steel castings.

From the preceding description it will be seen that I have provided a combined cast 100 steel and wrought iron yoke which may be used in a horizontal position and detachably connected to a coupler by means of an ordinary connecting key, the yoke possessing all the advantages of a wrought iron strap 105 which has greatest strength under tension and yet which will not be distorted or upset by the coupler connecting key under draft inasmuch as the key contacts directly with the steel castings which is well adapted to 110

resist the strains placed thereupon. The yoke is furthermore of simple construction and may be manufactured at relatively small expense.

5 Although I have herein shown and described what I now consider the preferred embodiment of my improvements, yet it will be understood that various changes and modifications may be made without departing from the spirit of the invention, and all such changes and modifications are contemplated as come within the scope of the claims appended hereto.

I claim:-

15 1. A yoke for railway draft gears comprising two slotted cast pieces each of which is provided with a boss, the slots extending through the bosses, and two wrought iron straps each of which is doubled upon itself and formed with an elongated recess at the bend and in which is received one of the bosses of the cast pieces, the portions of each strap being offset adjacent the rear of said bosses whereby the cast pieces are permanently held in position in the recesses formed by the bent straps.

20 2. A horizontal yoke for railway draft

gears comprising two wrought iron straps each of which is doubled upon itself and provided with an elongated recess located at 30 the front ends of the yoke arms, the portions of each strap to the rear of said recesses formed therein being brought together and a cast member secured to each of said straps, each cast member having a boss 35 seated within the elongated recess of the corresponding wrought iron straps.

3. A yoke for railway draft gears comprising two cast steel end pieces each of which is slotted to receive a coupler connecting key and provided with an elongated boss, two straps of wrought iron, each of which is bent around a boss of one of said cast pieces, said wrought iron straps having their rear ends bent to form the rear portion 45 of the yoke, and means for rigidly connecting the rear bent ends of said wrought iron straps, substantially as specified.

Signed this 13 day of March, 1914, in the presence of two subscribing witnesses.

ALFRED COPONY.
